UNITED STATES PATENT OFFICE.

ARTHUR B. SPERRY, OF NEW YORK, N. Y., ASSIGNOR TO WESTERN ELECTRIC COMPANY, INCORPORATED, OF NEW YORK, N. Y., A CORPORATION OF NEW YORK.

TELEPHONE SYSTEM.

Application filed February 15, 1923. Serial No. 619,086.

To all whom it may concern:

Be it known that I, ARTHUR B. SPERRY, a citizen of the United States of America, residing at New York, in the county of New York and State of New York, have invented certain new and useful Improvements in Telephone Systems, of which the following is a full, clear, concise, and exact description.

10 This invention relates to telephone systems and more particularly to systems wherein connections are established by means of machine switching apparatus.

In machine switching systems it is customary to connect blank bank terminals, or terminals of a line from which former service has been discontinued, to special trunks leading to a special operator's position, sometimes called an intercepting operator's position, so that a subscriber or operator whose connection has been extended to such blank terminals may be informed that the number of the called station has been changed, or service on the line of the called subscriber has been discontinued. In such cases it is necessary to prevent the operation of a message register or coin collect device at the calling end of the circuit if the call, which has been extended to the intercepting operator is from a subscriber and it is also desirable to provide supervision back to the originating end of the call if the call, which has been extended to the intercepting operator, is from a toll operator's position.

35 An object of the invention is therefore to provide an improved arrangement for enabling an operator to answer calls incoming over blank or unequipped terminals of a selector switch without causing a charge to be registered against the calling subscriber.

Another object of the invention is to provide an improved cord circuit to be used in connection with trunk circuits connected to blank terminals for answering calls from either a subscriber's station or a toll operator's position.

50 A feature of the invention consists in providing a cord circuit, for answering calls incoming over trunk circuits, with means for discriminating between calls incoming from the toll operator's position and calls incoming from a subscriber's line, said means functioning in one case to control a supervisory signal and in the other case

to prevent the operation of the call charging device.

This and other features of the invention will become more apparent after having considered the following detailed description in connection with Figs. 1 to 4, inclusive, of the drawings which, when arranged consecutively with Fig. 1 to the left, show one embodiment of the invention.

Fig. 1 of the drawings shows a portion of a cord circuit at a toll operator's position and a portion of the outgoing end of a trunk circuit to which the cord circuit has access. Fig. 2 shows schematically the incoming end of the toll trunk circuit, a portion of a toll transmission selector circuit and a subscriber's station having access to a line switch and a selector switch. Fig. 3 shows a combined toll and local connector. The combined toll and local connector has access to the subscriber's station B and to an intercepting trunk circuit I-T. Fig. 4 shows the incoming end of the intercepting trunk circuit and the intercepting operator's cord circuit K for answering calls over the trunk circuit. The circuit shown in Figs. 1 and 2, with the exception of the subscriber's station A together with its associated switches shown in Fig. 2, are fragmentary portions of the drawings shown in the copending application of Ray L. Stokely, Serial No. 412,795, filed September 25, 1920. The same reference characters have been employed in this application as are employed in the Stokely application so that the elements of this disclosure may be readily found in the aforementioned reference.

A call from station A for a subscriber at station B will first be described. Upon the removal of the receiver by the calling party at substation A, the line of substation A is automatically extended in the well known manner by the line switch LS to a first selector switch SL. The subscriber now operates his dial 90 to set the first selector opposite a group of trunks having access to a plurality of connector switches, whereupon the selector switch automatically seizes one of these switches such as FC. The line relay A-6 of the connector switch now operates over a circuit extending from ground, through the lower winding of relay A-6, upper normal contacts of relay D-6, terminal 34, brush

30, terminal 44, brush 40, thence through the calling substation loop, brush 41, terminal 45, brush 31, terminal 35, lower inner normal contacts of relay D-6 and upper winding of 5 relay A-6 to grounded battery. Relay A-6 in operating completes an obvious circuit through its alternate contacts for slow to release relay B-6. Relay B-6 in attracting its armature 616 grounds test terminal 36; its uppermost armature connects ground over lead 650 to the test terminal 527 of the toll selector switch TTS, for the purpose of rendering the connector FC busy at the selector switch TTS; and in attracting 10 its lower armature prepares a circuit for slow to release relay 619 and the vertical magnet 618 over a path extending from grounded battery, through the winding of magnet 618, winding of relay 619, right-hand contacts of off-normal switch 620, lower alternate contacts of relay B-6 and normal contacts of relay A-6 to ground. The subscriber now turns the dial for the tens 15 digit and the relay A-6 transmits impulses over the said circuit to the vertical magnet 618 to raise the brushes of the connector to the desired level. The first impulse for the vertical magnet passes over the path previously traced by way of the 20 normal contacts of the off-normal switch 620; the succeeding impulses pass by way of contact 622 of the off-normal switch 620 and the upper armature and front contact of slow to release relay 619, which relay 25 is energized at the first impulse of the tens series and remains energized during this series.

When the impulses cease, relay 619 releases, connecting the rotary magnet 623 to 40 the back contact of the impulse relay A-6 over a circuit extending from the back contact of relay A-6, through the lower alternate contacts of relay B-6, contacts 622 of off-normal switch 620, normal contacts of 45 relay 619, inner left-hand contacts of relay G-6, conductor 625, uppermost contacts of relay H-6 and winding of rotary magnet 623 to grounded battery.

The operator now turns the dial for the 50 units digits. At each deenergization of the line relay A-6, in response to the dialing of the units digits, the impulse circuit for rotary magnet 623 is closed thereby advancing the brushes of the connector switch a 55 number of steps corresponding to the digit transmitted. Relay E-6 is also energized, in parallel with magnet 623, when the first units impulse is transmitted. Relay E-6 which is slow to release remains operated 60 during the impulse period. An interval after the last impulse is transmitted, relay E-6 releases.

Assuming that the number dialed corresponds to the number of the station B and that the brushes of the connector have been

moved into engagement with the terminals 76 to 78 inclusive of station B and that the line of station B is idle, relay H-6 will be operated and ringing current will now be applied to the station B. The circuit for 70 operating relay H-6 may be traced from ground, through the upper inner contacts of relay B-6, conductors 615, and 631, right-hand normal contacts of relay G-6, upper winding of relay H-6, conductor 629, outer 75 right-hand normal contacts of relay E-6, brush 627 to grounded battery at terminal 78. Relay H-6 in operating locks to ground at the contacts of relay J-6 under control of relay B-6. The path for the 80 ringing current may be traced as follows: ground, through the ringing machine 680, upper winding of relay F-6, back contact and armature 637 of relay F-6, armature 681 and front contact of relay H-6, brush 684, terminal 77, through the bell of station B, terminal 76, brush 683, upper inner contacts of relay H-6, upper normal contacts of relay F-6, to grounded battery.

When the party at station B answers, 85 relay F-6 will energize due to an increase in the amount of current flowing through its upper winding. Relay F-6, in operating, disconnects ringing current from the called station, renders the tip and ring talking conductors of the connector switch FC continuous, and locks over a path extending from grounded battery, through the lower winding, armature 635 and front contact of relay F-6, back contact and armature 90 602 of relay K-6, upper outer armature and front contact of relay B-6 and inner left-hand contacts of relay J-6 to ground. As soon as relay F-6 operates, a circuit is closed for the energization of back bridge 95 relay D-6 over a path extending from grounded battery through the upper winding of relay D-6, contacts 690 of relay K-6, upper alternate contacts of relay F-6, upper inner contacts of relay H-6, brush 683, terminal 76, through the loop of 100 station B, terminal 77, brush 684, front contact and armature 681 of relay H-6, armature 637 and front contact of relay F-6, contacts 691 of relay K-6 and lower winding of relay D-6 to ground. Relay D-6, 105 in operating, reverses the flow of current over the calling end of the connector circuit and causes the operation of the message register 50 of the calling substation A in 110 the manner well understood in the art.

Assuming that the called substation is 115 busy, ground potential will be present on the test terminal 78 of the called station B and when brush 627 arrives at terminal 78, relay H-6 will not be operated. Relay G-6 will operate over a circuit extending from grounded battery, through the winding of relay G-6, back contact and armature 120 642 of relay H-6, contact 640 of slow 125

to release relay E-6, conductor 628, brush 627, to ground at terminal 78. Relay G-6 in attracting its outer left-hand armature connects a source of busy tone 645 to the 5 calling station to indicate that the called subscriber is busy.

Upon the completion of conversation, the restoration of the receivers of the calling and called stations to the switchhooks releases relays A-6 and D-6. Relay A-6 10 in releasing, releases relay B-6. An obvious circuit is then completed for release magnet 686 through the left-hand contacts of off-normal switch 620, whereupon the 15 connector switch is restored to normal position.

A call by the subscriber of station A for a number of a line to which no station is connected will now be described. The 20 terminals of such numbers are connected to trunk circuits such as I-T leading to the intercepting operator's position. If the subscriber at station A dials a number corresponding to the trunk I-T, the connector 25 FC will be set on the trunk terminals 93, 94 and 95 in a manner similar to that previously described, after which ringing current will be automatically applied to the trunk to light the lamp 152 at the intercepting operator's position, as an indication 30 that a calling line is connected to the trunk I-T. The path of the ringing current may be traced as follows: grounded battery, through the upper normal contacts of relay 35 F-6, upper inner contacts of relay H-6, brush 683, terminal 93, condenser 101, right-hand winding of relay 153, outer left-hand contacts of relay 154, terminal 94, brush 684, armature 681 and front contact of relay 40 H-6, armature 637, back contact and upper winding of relay F-6 and source of ringing current 680 to ground. Relay 153 operates in this circuit and locks over a circuit including the outer contacts and the left-hand winding of relay 153 and the inner 45 left-hand contacts of relay 154, and completes an obvious circuit through its left-hand contacts for lamp 152. Lamp 152 in lighting indicates to the intercepting operator that a calling line is connected to the 50 trunk I-T.

The operator will thereupon insert plug 55 106 into jack 107 whereupon relay 110 will be operated over a path extending from grounded battery, through the right-hand normal contacts of relay 112, winding and left-hand normal contacts of relay 110, lower normal contacts of relay 114, rings of plug 106 and jack 107, and right-hand normal contacts of relay 154 to ground. Relay 110, in operating, completes a circuit for relay 154 of the trunk circuit over a path extending from ground, through the winding of relay 154, sleeves of jack 107 and plug 60 106, left-hand alternate contacts and wind-

ing of relay 110 and right-hand normal contacts of relay 112 to grounded battery. Relay 154, in attracting its inner left-hand armature, opens the locking circuit for relay 153 which releases, extinguishing the lamp 70 152, and in attracting its right-hand armature renders the ring conductor of the trunk circuit I-T continuous. Relay 110 in attracting its outer right-hand armature completes an obvious circuit for slow-to-pull-up relay 117. Relay 117 in operating completes an obvious circuit for the energization of slow-to-pull-up relay 114. Relay 114 in attracting its lower armature, renders the ring talking conductor of the cord circuit K continuous. Before the relay 114 75 operates, however, to render the ringing conductor of the cord circuit K continuous, the ringing current is tripped over a circuit extending from ground, through the inner right-hand contacts of relay 110, lower normal contacts of relay 114, rings of plug 106 and jack 107, right-hand alternate contacts of relay 154, terminal 94, brush 684, armature 681 and front contact of relay H-6, 80 armature 637, back contact and upper winding of relay F-6, and source of ringing current 680 to ground. Relay F-6 operates in this circuit thereby disconnecting the source of ringing current from the trunk 85 I-T and rendering the tip and ring talking conductors of the connector circuit continuous. Relays 114 and 117 are made slow-to-pull-up to insure that ringing current 90 will be tripped before the operator can connect her head set to the trunk circuit so as to avoid disagreeable clicks in the operator's ear. Relay 114, in operating, closes a high resistance bridge across the tip and ring 95 conductors of the cord circuit over a path extending from the tip conductor of the cord circuit K through retardation coil 130, windings of relay 131 and polarized relay 132, right-hand normal contacts of key 133 100 to the ring conductor of the cord circuit K. The polarized relay 132 is a test relay which determines whether or not the intercepted 105 call is from a toll operator. If the call is not from a toll operator, but from a subscriber's line, the flow of current through the winding of relay 132 is in such a direction as to prevent the operation of relay 132. The circuit under these conditions is as follows: from battery through the upper winding of relay D-6 (Fig. 3), contact 690 of 110 relay K-6, upper alternate contact of relay F-6, brush 683, terminal 93, tip conductor of jack 107, tip conductor of plug 106, retardation coil 130, windings of relays 131 and 132 in series, right hand normal contacts of key 133, lower alternate contact of relay 114, ring conductor of plug 106, ring conductor of jack 107, right hand alternate contact of relay 154, terminal 94, brush 684, 115 armature 681 and alternate contact of relay 120 132. The circuit under these conditions is as follows: from battery through the upper winding of relay D-6 (Fig. 3), contact 690 of relay K-6, upper alternate contact of relay F-6, brush 683, terminal 93, tip conductor of jack 107, tip conductor of plug 106, retardation coil 130, windings of relays 131 and 132 in series, right hand normal contacts of key 133, lower alternate contact of relay 114, ring conductor of plug 106, ring conductor of jack 107, right hand alternate contact of relay 154, terminal 94, brush 684, 125 armature 681 and alternate contact of relay 130.

H-6, armature 637 and alternate contact of relay F-6, contact 691 of relay K-6, lower winding of relay D-6 to ground. In the circuit traced the positive side of the 5 battery is connected to the ring conductor of the cord circuit K. Relay 132 will not operate unless the positive side of the battery is connected to the tip conductor of the cord circuit K. Hence, relay 132 does 10 not operate at this time, and relay 135 therefore remains normal. Under these circumstances, the back-bridge relay D-6 of the connector switch FC will not operate due to the high resistance of the winding of the 15 polarized relay 132 in series with it. Relay 131, however, operates over the circuit traced in series with relays 132 and D-6, thus opening at its armature, the circuit through the winding of relay 112 to ground at the 20 upper alternate contact of relay 114. Relay 112 is made slow-to-pull-up so that it will not operate during the time interval between the operation of relays 114 and 131 and furnish a false disconnect signal by 25 lighting lamp 138. Since relay D-6 does not operate, the current is not reversed over the calling line and consequently the message register of the calling line will not be operated.

30 The operator after inserting plug 106 into jack 107 will actuate key 139 thereby connecting the operator's telephone set O in operative relationship with the calling line. The operator may then converse with the 35 calling party and inform him that service has been discontinued on the line which he has called or give him any other information which he desires.

40 Upon the completion of conversation, the restoration of the receiver to switchhook at station A causes the release of automatic switches in the manner well known. The removal of the current from the talking conductors of the trunk circuit I-T when the 45 switch FC releases, causes the deenergization of relay 131 of the cord circuit K. Relay 131 in releasing completes a circuit for relay 112 over a path extending from grounded battery, through the winding of relay 112, 50 contacts of relay 131, left-hand contacts of key 133, and upper contacts of relay 114 to ground. Relay 112 operates in this circuit, and in attracting its left-hand armature, completes an obvious circuit for lamp 138.

55 Relay 112 in attracting its right-hand armature opens the circuit and causes the release of relay 110. The release of relay 110 opens the circuit of slow-to-pull-up relay 117 which releases, in turn releasing relay 114. When 60 relay 112 operates, a circuit is completed to operate relay 115 of the cord circuit K over a path extending from ground, through the winding of relay 154 sleeves of jack 107 and plug 106, winding of relay 115, and right-hand alternate contacts of relay 112 to

grounded battery. Relay 115 operates 70 closes a circuit to maintain relay 112 operated after relay 114 releases. Relay 115 has a high resistance winding, so that relay 154 now releases thereby rendering the ring conductor of the trunk circuit I-T discontinuous and connecting the alternating current relay 153 across the trunk circuit. It will, thus be seen, that, if the operator fails to remove the plug 106 from the jack when the disconnect lamp 138 is lighted, the trunk circuit I-T is nevertheless available for recall. If before the plug 106 is removed from the jack 107, a recall signal is received, it is necessary for the operator to momentarily remove the plug 106 from the jack 107 so as to restore the operated relays of the cord circuit K to normal so as to prepare these relays for another cycle of operation. 85

A call by the toll operator for a station to which the connector FC has access but on which the service has been discontinued will now be described. It will be assumed that the trunk I-T is connected to the terminals 90 corresponding to the number of the station desired.

Extension of the connection from the operator's position to the connector switch FC is established in the manner described in detail in the copending application heretofore mentioned and a detailed description of the operation of the connector switch will only be given herein. The operator after inserting the plug TT into the jack TSJ (Fig. 1) and after actuating the dialing key DK proceeds to operate the dial D to send sets of impulses corresponding to the number desired, whereupon the selector switches SS and TTS will be set to select the terminals of the connector switch FC to which the trunk I-T is connected. At this time, relays A-2, E-72, I-2, B-2, D-2, A-5, D-4, A-6, D-5, B-5, B-6 and J-6 will be energized in the manner fully set forth in the above mentioned application. 105

The seizure of the connector causes the closing of the following circuit for the impulse relay A-6: grounded battery, upper winding of relay A-6, conductors 604 and 605, left-hand winding of relay J-6, conductors 606 and 607, lowermost armature and back contact of relay K-6, ring conductor 646, terminal 544, brush 534, conductor 545, front contact and armature 532 of relay D-5, left-hand armature and front contact of relay A-5, ring conductor 546, lower right-hand winding of repeating coil 406, resistance 460, conductor 422, left-hand armature and front contact of relay D-4, resistance 423, conductor 424, resistance 461, upper right-hand winding of repeating coil 406, conductor 547, armature 531 and front contact of relay D-5, conductor 548, brush 533, terminal 549, conductor 610, upper ar-

mature and back contact of relay K—6, conductor 611, conductor 612, and lower winding of relay A—6 to ground. Relays A—6 and J—6 operate in this circuit, the 5 latter at its innermost right-hand armature, closing a locking circuit for itself as follows: grounded battery, right-hand winding and inner right-hand armature and front contact of relay J—6, conductor 614, conductor 631, conductor 615 to ground at the armature 616 and front contact of slow-to-release relay B—6, which operated upon the energization of the impulse relay A—6. Relay B—6, in operating, grounds the 10 sleeve wire 617 leading to the test multiple terminals of the local selectors, this circuit extending from ground, armature 616 and front contact relay B—6, conductor 615, to conductor 617. The return of the dial to 15 normal in transmitting the tens digit interrupts the circuit of relay A—2 which in turn interrupts the circuit of the impulse relay A—5, which in vibrating its left armature causes the impulse relay A—6 of the 20 connector to transmit impulses to the vertical magnet 618 of the connector over the following circuit: grounded battery, magnet 618, slow-to-release relay 619, right-hand normal contacts of the off-normal switch 25 620, conductor 621, lower armature and front contact of relay B—6 to ground at the armature and back contact of the impulse relay A—6. At the first step of the connector, the springs of the off-normal switch 30 620 are shifted and the succeeding impulses are transmitted by way of the upper armature and front contact of relay 619 and the contact 622 of the off-normal switch 620 now closed. The connector brushes are thus lifted 35 to the desired level and upon the cessation of the impulses, impulse relay A—6 remains energized and relay 619 in series with the vertical magnet 618 releases thereby preparing the circuit for the rotary magnet 623. 40

The units impulses pass through the back contact of the impulse relay A—6, lower armature and front contact of relay B—6, conductor 621, off normal contacts 622, armature and back contact of slow-to-release relay 619, conductor 624, inner left-hand armature and back contact of relay G—6, conductor 625, uppermost armature and back contact of relay H—6, and winding of rotary magnet 623 to grounded battery. The connector is thus stepped into engagement with the terminals of trunk I—T. 45

If the trunk I—T is idle, grounded battery will be present on the test terminal 95 and the following circuit will be closed to operate relay H—6: grounded battery, at test terminal 95, brush 627, conductor 628, right-hand armature and back contact of relay E—6, conductor 629, upper winding of relay H—6, conductor 630, right-hand armature and back contact of relay G—6, conductor 631, conductor 615, and armature 616 of relay B—6 to ground. Relay H—6, in attracting its armature 632, locks itself to the grounded sleeve wire 650 and extends 70 this grounded conductor over conductor 633, middle right-hand armature and front contact of relay J—6, conductor 634 to the winding of relay K—6. Relay K—6, in attracting its armature 602, disconnects the 75 grounded sleeve wire 650 from the control lead 600, leading back to the relay D—4 releasing the latter relay. Relay D—4, in retracting its outer right-hand armature, operates relay F—4 over the following circuit: 80 grounded battery, through the winding of relay F—4, conductor 428, outer right-hand armature and back contact of relay D—4, conductor 429, armature 523 and front contact of relay D—5, conductor 518 and conductor 503 to ground at the right-hand armature and front contact of relay B—5. Relay F—4, in attracting its outer right-hand armature, closes a substitute ground 85 to hold up the relay F—6 to prevent ringing 90 current from being transmitted out over the connector at this time. This circuit may be traced from ground, through the right-hand armature and back contact of relay E—4, conductor 430, right-hand armature and back contact of relay B—4, outer right-hand armature and front contact of relay F—4, control conductor 414, contacts 535 of relay D—5, conductor 538, brush 539, terminal 95 540, conductor 600, front contact and armature 635 of relay F—6, lower winding of relay F—6 to grounded battery. The operation of relay K—6, to cause the reversal 100 of the direction of the current flowing in the loop leading back to the toll operator's position, would cause the deenergization of relay F—6 and unless a substitute circuit is provided for holding relay F—6 the ringing operation would automatically take 105 place. This is prevented by applying ground to the control conductor 600 over the circuit traced to hold the relay F—6 until the operator by depressing the ringing key, as will be explained hereinafter, releases relay F—6 to start the automatic ringing operation. The release of the relay D—4 and the energization of relay F—4, as described, reverses the direction of current flow in the talking conductors leading 110 back to the toll operator's position. 115

After having turned the dial for the last time the operator restores her dialing key DK which disconnects the dial from the tip of the plug causing the release of the relay A—2 and causes the closure of an energizing circuit for the right-hand winding of relay C—2, and for relays B—43 and A—2. Relay A—2 being marginal, releases under 125 this condition and in retracting its left-hand armature deenergizes relay I—2, which, in 130

releasing, causes the release of relay D—2. The polarized relay F—2 is now bridged across the trunk circuit, the bridge extending from the upper talking conductor 212, conductor 211, winding of polarized relay F—2, conductor 210, inner right-hand armature and front contact of relay B—2, conductors 209, left-hand winding of relay C—2, armature and front contact of relay C—2, conductor 207, outer left-hand armature and back contact of relay H—2, conductor 206, to the lower talking conductor 205. The reversal of the direction of current in the talking conductors due to the operation of relay F—4 causes the relay F—2 to operate closing the following circuit for relay G—2: grounded battery, winding of relay G—2, conductor 224, contact 225 of relay F—2, conductor 226, inner left-hand armature and front contact of relay B—2 to ground. Relay G—2 locks over the following circuit: grounded battery, winding of relay G—2, conductors 224 and 229, front contact and armature 230 of relay G—2, conductor 231, to ground at the inner left-hand armature of relay B—2. Relay G—2 connects the talking conductors 212 and 205 through to the talking conductors of the cord circuit whereupon the trunk and toll relay B—43 operates in series with the relay A—5 and lights the supervisory lamp 100 as a ringing signal to the toll operator. Relay G—2 disconnects the bridge including the relay C—2 and A—2 from the talking conductors 212 and 205.

The operator now actuates her ringing key RK which impresses alternating current upon the talking conductors, to operate the alternating current relay C—4, which in attracting its armature operates the relay E—4. This relay in attracting its armature opens the circuit heretofore traced for holding relay F—6 energized. Relay F—6 thereupon releases and in retracting its armature 637 connects ringing current to the selected trunk through the upper winding of relay F—6 and causes the operation of a signal 152 at the intercepting operator's position in the manner previously described. This ringing current is automatically continued until the intercepting operator connects to the trunk over which the call has been received.

The intercepting operator noting the lighting of lamp 152 inserts the plug 106 into the jack 107, whereupon the ringing current is tripped and relays 110, 117, 114 and 154 are operated and the bridge including retardation coil 130 and relays 131 and 132 are placed across the cord K in the manner previously described. A circuit is now closed to operate relays 131 and 132 as follows: grounded battery, through the winding of relay A—4, (which being marginal does not operate) back contact and left-hand

armature of relay D—4, conductor 422, resistance 460, lower right-hand winding of repeating coil 406, front contact and left-hand armature of relay A—5, armature 532 and front contact of relay D—5, conductor 545, brush 534, terminal 544, conductor 646, lowermost armature and front contact of relay K—6, front contact and armature 637 of relay F—6, armature 681 and front contact of relay H—6, brush 684, terminal 94, right-hand alternate contacts of relay 154, rings of jack 107 and plug 106, lower alternate contact of relay 114, right-hand normal contacts of key 133, windings of relays 132 and 131 and coil 130, tips of plug 106 and jack 107, terminal 93, brush 683, upper inner contacts of relay H—6, upper alternate contacts of relay F—6, upper alternate contacts of relay K—6, conductor 610, terminal 549, brush 533, upper inner contacts of relay D—5, conductor 547, upper right-hand winding of repeating coil 406, resistance 461, conductor 424 and inner right-hand normal contact and armature of relay D—4 to ground. In the circuit traced the positive side of the battery is connected to the tip conductor of the cord circuit K hence the direction of the current flowing through the winding of the polarized relay 132 is in the proper direction to cause this relay to operate. Relay 131 operated, prevents the operation of relay 112 and the subsequent lighting of the lamp 138 at this time in the manner previously described.

Relay 132, in operating, closes an obvious circuit for relay 135. Relay 135, in operating, locks over a path including grounded battery, winding and left-hand contacts of relay 135 and outer right-hand contacts of relay 110 to ground. Relay 135, in operating, closes a short circuit around the winding of relay 132 thereby reducing the resistance in series with relay A—4 to such an extent as to permit the operation of relay A—4. Relay A—4, in operating, completes an obvious circuit for relay B—4. Relay B—4, in attracting its right-hand armature, applies ground to the conductor 414 to hold relay F—6 energized independently of relay E—4. Relay B—4, in attracting its left-hand armatures, disconnects the battery and ground supplied through the windings of relay A—5 to the talking conductors 407 and 408 leading back to the operator's position which causes the deenergization of relay B—43. Relay A—5 remains operated through its windings in series under the control of relay B—4. Relay B—43 in retracting its armature extinguishes the supervisory lamp which notifies the operator that the intercepting operator has responded.

After the completion of conversation between the toll operator and the intercepting operator, the intercepting operator may re-

move plug 106 from jack 107 whereupon relays A-4 and B-4 release. The release of relay B-4 again connects battery and ground through the windings of relay A-5 to the conductors 407 and 408 causing relay B-43 to operate and lamp 100 at the toll operator's position to light as a disconnect signal. The operator noting this signal may remove plug TT from the jack TSJ. The circuit for relay A-5 is thereby opened whereupon said relay A-5 retracts its armatures. Relay A-5 in releasing causes the restoration of the selector switch TTS to normal in the manner fully described in the aforementioned application. When the toll transmission selector TTS restores to normal, the circuit for relays A-6 and B-6 and J-6 are opened which results in the closure of the following circuit for the release magnet 686 of the connector circuit: grounded battery, winding of magnet 686, left-hand contacts of the off-normal switch 620, back contact and lowermost armature of relay D-6, and lower armature and back contact of relays B-6 and A-6 to ground. Magnet 686 in operating restores the connector switch FC to normal in the manner well known in the art. Connector switch FC upon reaching normal position restores the off-normal switch 620.

A key 133 is provided at the intercepting operator's position to enable the intercepting operator to flash the toll operator. Actuation of key 133 opens the bridge across the cord circuit K whereupon relays A-4 and B-4 are in turn deenergized. The release of relay B-4 again places relay A-5 in circuit with relay B-43 which operates lighting lamp 100. It will thus be seen that by repeatedly actuating key 133, lamp 100 may be flashed thereby informing the operator at the toll position that the intercepting operator desires her attention. Condensers 165, 166 are provided in the cord circuit K to prevent varying the resistance of the high resistance bridge, which would occur due to the shunt formed by the telephone set O, or in case two listening keys were operated simultaneously due to the parallel combination which would be formed.

What is claimed is:

1. In a telephone system, a subscriber's line, a call charging device associated therewith, an operator's position, a signal thereat, a trunk circuit, means including an automatic switch for extending a connection from said line or said operator's position to said trunk circuit, a connecting circuit for answering calls incoming over said trunk circuit, and means in said connecting circuit to discriminate between calls over said trunk circuit, said discriminating means serving to prevent operation of said call charging device when a call from said subscriber's line is answered and serving to con-

trol said signal when a call from said operator's position is answered.

2. In a telephone system, subscribers' lines, call charging devices associated therewith, an operator's position, a signal thereat, a trunk circuit, means including an automatic switch for extending a connection from said line or said position to said trunk circuit, means including said automatic switch for extending a connection from one of said subscriber's lines to another, means for automatically operating the call charging device of the calling line upon the response of the called subscriber, a connecting circuit for answering calls over said trunk circuit, means operative when said trunk has been selected by a calling subscriber for preventing the operation of said call charging means, and means operative when said trunk has been selected from said position for causing the operation of said signal.

3. In a telephone exchange system, a subscriber's line, a cord circuit, a trunk circuit, a link circuit, switching means for extending a connection from said line or said cord circuit to said trunk circuit, means connected across the trunk circuit when said trunk circuit is seized for controlling the application of current to the line or the cord circuit, and means effective upon the connection of the link circuit to the trunk circuit to operate said second named means if the call originated at said cord circuit, but ineffective to operate said second named means if the call originated at said subscriber's line.

4. In a telephone exchange system, an operator's position, a calling subscriber's line, a second operator's position, a cord circuit thereat, a trunk line extending to said second position, switching means for extending a connection from said subscriber's line or said first mentioned operator's position to said trunk line, current controlling means connected across said trunk line when a connection is extended to said trunk line, and means in said cord circuit effective in response to the connection of the cord circuit with the trunk line to operate the current controlling means if the call is from said first mentioned operator's position, but ineffective in response to the connection of the cord circuit with the trunk line to operate the current controlling means if the call is from said subscriber's line.

5. In a telephone system, a cord circuit, a subscriber's line, a trunk circuit, a connector switch, means including said connector switch for extending a connection from said cord circuit or said subscriber's line to said trunk line, a back bridge relay connected in circuit with said trunk line when a connection is extended to said trunk line, an operator's link circuit, means in said link circuit operative to operate said back bridge relay

if a call originating at said cord circuit is answered, and means in said link circuit for preventing the actuation of said back bridge relay if a call originating at said subscriber's line is answered.

6. In a telephone system, a trunk circuit, a connector switch for extending a subscriber's line or a toll operator's position to said trunk circuit, a back bridge relay connected across the talking conductors of said trunk circuit when a connection is extended thereto, a cord circuit, a bridge of variable resistance for the cord circuit, means in the cord circuit responsive to the linking of said cord circuit with said trunk circuit for automatically bridging all of said resistance across the cord circuit, means for maintaining the resistance of said bridge unchanged to prevent the actuation of said back-bridge relay if a call originates at said subscriber's line, and means serving to automatically reduce the resistance of said bridge across said cord circuit to permit the operation of said back-bridge relay if the call originates at said toll operator's position.

7. In a telephone system, a calling line, an operator's position, a trunk circuit, means including automatic switches for extending a call from said calling line or said operator's position to said trunk circuit, a cord circuit for answering incoming calls over said trunk circuit, a bridge of either high or low resistance for said cord circuit, and means in said cord circuit for automatically maintaining said bridge across said cord circuit at high resistance or for reducing it to a low resistance bridge dependent upon whether the call is from said subscriber's line or said operator's position.

8. In a telephone system, a calling line, an operator's position, a trunk circuit, means including automatic switches for extending a call from said calling line or said operator's position to said trunk circuit, a cord circuit for answering incoming calls over said trunk circuit, a bridge of either high or low resistance for said cord circuit, and a polarized relay in said cord circuit for reducing the resistance of said bridge across said cord circuit from high to low dependent upon whether the incoming call is from said subscriber's line or from said operator's position.

9. In a telephone system, a subscriber's

line, a call charging device associated therewith, an operator's position, a signal thereat, a trunk circuit, means including an automatic switch for extending the connection from said line or said operator's position to said trunk circuit, a connecting circuit for answering calls incoming over said trunk circuit, means in said connecting circuit to discriminate between calls over said trunk circuit, said discriminating means serving to prevent the operation of said call charging device when a call from said subscriber's line is answered, and serving to control said signal when a call from said operator's position is answered, a disconnect signal in said connecting circuit, and means responsive to the breaking down of an established connection by the calling subscriber or operator for displaying said disconnect signal.

10. In a telephone exchange system, a subscriber's line, a call charging device associated therewith, an operator's position, a supervisory signal thereat, a trunk circuit, a trunk signal associated therewith, means including an automatic switch for extending a connection from said line or said operator's position to said trunk circuit and for displaying said trunk signal, a connecting circuit for answering calls, means responsive to the answering of a call incoming over said trunk circuit for restoring said trunk signal, means in said connecting circuit to discriminate between calls over said trunk circuit, said discriminating means serving to prevent the operation of said call charging device when a call from said subscriber's line is answered and serving to control said signal when a call from said operator's position is answered, a disconnect signal in said connecting circuit, means responsive to the breaking down of an established connection by the calling subscriber or operator for displaying said disconnect signal, and means responsive to the extending of a second connection to said trunk circuit for again displaying said trunk signal, irrespective of the relationship then existing between said trunk circuit and said connecting circuit.

In witness whereof, I hereunto subscribe my name this 6th day of February A. D., 1923.

ARTHUR B. SPERRY.
